METAL FORMING APPARATUS

Harry Blount, Baltimore, and Carl V. Lundeen, Towson, Md., assignors to Western Electric Company, Incorporated, New York, N. Y., a corporation of New York

Application April 8, 1942, Serial No. 438,152

5 Claims. (Cl. 205—25)

This invention relates to metal forming apparatus and more particularly to apparatus for drawing strip material.

For certain purposes it is essential to use metal strips or ribbons of extremely uniform and precise dimensions. However, strip material of this character is not available in the open market and it is an object of the present invention to provide an effective and efficient apparatus for drawing strip material to precise dimensions.

This invention may be embodied in a strip drawing apparatus having a pair of stationary sizing members through which strip material is drawn. These sizing members are provided with a number of inserts made of a hard, wear-resistant material which act as the drawing members and which may be successively used as one set of inserts becomes worn.

Other advantages and objects of this invention will appear from the following detailed description taken in conjunction with the accompanying drawing, wherein

Fig. 1 is a side elevation of a strip forming apparatus;

Fig. 2 is an enlarged detail view showing a strip sizing assembly forming a part of the strip forming apparatus shown in Fig. 1;

Fig. 3 is an end view of the assembly shown in Fig. 2;

Fig. 4 is an enlarged detail view showing a preferred embodiment of a sizing member employed in the sizing assembly, and

Fig. 5 is a sectional view taken along the line 5—5 of Fig. 4.

Referring now to the drawing, an apparatus for drawing strip material is shown in Fig. 1, having a supply reel 6 containing strip material 7, the reel being mounted on a stand 8. The material is led over idler pulleys 9 and 10 mounted on a frame 11 and then passed over a conventional tensioning mechanism 12, over an idler pulley 13 also mounted on the frame 11, and through a sizing assembly 14. A lubricating compound, such as a solution of a water soluble oil, is fed to the sizing assembly by a recirculating system of conventional design (not shown) to lubricate the sizing members. From the sizing assembly 14 the strip material is passed through a conventional wiping mechanism 15 and over power driven capstans 17 and 18, which pull the strip through the sizing assembly 14 and associated mechanisms. The wiping mechanism 15 removes excess lubricating compound from the strip material and cleans the material. The strip material is final-

ly wound on a take-up reel 19 driven by a motor 20 through a chain 21 running over gears 22 and 23.

A thin strip of material cannot be wrapped completely around a capstan, as is usually done with wires, and if only one capstan were used, it would be necessary to use a very large capstan to provide sufficient surface to draw the strip material through the sizing attachment. Consequently, it is advisable to use a plurality of capstans and in the specific embodiment of the invention illustrated in the drawing two capstans 17 and 18 are shown. The peripheral surfaces of the capstans 17 and 18 are faced with a suitable friction material 16 to prevent slippage of the strip material. Cork has been found to be the material best suited for use as the friction material 16.

Enlarged views of the sizing assembly 14 are shown in Figs. 2 and 3. The sizing assembly comprises a housing 24 supported by a bracket 25 bolted to the frame 11 and a pair of stationary sizing members 26 and 27 are positioned in the housing. As may be seen in Figs. 4 and 5, these sizing members are substantially cylindrical in shape; however, the end portions 31 thereof are squared so as to be non-rotatably engaged by the housing. Four inserts 32 of wear-resistant material, such as tungsten carbide, are positioned longitudinally on the cylindrical portion of the sizing members and provide drawing surfaces 34 for engaging and sizing the strip material.

The distance between the drawing surfaces 34, and consequently the amount of drawing performed upon the strip material as it is drawn therebetween, is adjusted by a pair of threaded members 28 which engage the squared portion 31 of the upper sizing member 26 and which are mounted in the top of the housing. A pointer 29 is associated with these threaded members and indicates the adjustment of the upper sizing member. Since the end portions of the sizing members are squared, and since the sizing members are closely engaged by the die housing at their end portions, it will be apparent that when the end portions are also engaged by removable plates 30, which are bolted to the housing, rotation of the sizing members is prevented. Removal of the sizing members is accomplished by removing the plates 30, when the sizing members may be easily withdrawn.

In the operation of this apparatus, the wear-resistant inserts act as the drawing surfaces and as one set of inserts becomes worn, a new set

of inserts may be readily placed in drawing position merely by removing the plates 30, withdrawing the sizing members, rotating them a quarter of a revolution each and then placing them back in the housing. When all of the inserts in a particular sizing member become worn, the sizing member is replaced with one having inserts of the proper profile. The worn inserts may be reconditioned by grinding and the sizing member then reused.

It will be obvious that by using a plurality of inserts with each sizing member considerable savings will be effected, since it will then not be necessary to replace the sizing member, but merely to rotate it to change the position of the inserts as they become worn. An equally important advantage, however, of this apparatus is the improvement in the uniformity and the accuracy of the dimensions of the material sized thereby.

While but one embodiment of this invention has been described, it will be understood that many changes and alterations may be made therein without departing from the scope of the present invention as defined in the annexed claims.

What is claimed is:

1. A strip sizing apparatus comprising a die housing, a rectangularly recessed portion formed in said die housing, a removable member associated with said die housing and cooperating therewith to form rectangular slotted portions, a pair of cylindrical dies, the ends of said dies being squared to fit into said slotted portions and to be movable longitudinally with respect thereto to adjust the separation between the dies, means for limiting said longitudinal movement, and a number of axially extending inserts of wear resistant material positioned in the surfaces of the dies.

2. A strip sizing apparatus comprising a die housing, a rectangularly recessed portion formed in said die housing, removable members associated with said die housing and cooperating therewith to form rectangular slotted portions, a pair of cylindrical dies, the ends of said dies being squared to fit into said slotted portions and to be movable longitudinally with respect thereto to adjust the separation between the dies, and

a number of axially extending inserts of wear resistant material positioned in the surfaces of the dies.

3. A strip sizing apparatus comprising a die housing, a rectangular recessed portion formed therein, a removable member associated with the die housing and cooperating therewith to form rectangular slotted portions, a pair of cylindrical sizing dies, a plurality of spaced inserts of wear resistant material in said dies, said inserts forming with said dies a substantially continuous cylindrical surface, said inserts extending substantially parallel to the axis of the dies, the ends of said dies being squared to fit into said slotted portions and to be movable longitudinally with respect to said slotted portions, said slotted portions preventing said dies from rotating.

4. A strip sizing apparatus comprising a die supporting base, a die housing mounted thereon having an apertured wall through which the strip may pass, a pair of forwardly extending members integral with said wall and adjacent said aperture, said members having rectangular slotted portions and projections forming extensions of said slots, plates having recesses fitting over said projections, said plates extending into said rectangular slotted portions to form guideways, a pair of cylindrical dies having rectangular ends extending into said guideways, and means for adjusting the position of said rectangular die ends in said guideways.

5. A strip sizing apparatus comprising a die supporting base, a die housing mounted thereon having an apertured wall through which the strip may pass, a pair of forwardly extending members integral with said wall and adjacent said aperture, said members having rectangular slotted portions and projections forming extensions of said slots, plates having recesses fitting over said projections, said plates extending into said rectangular slotted portions to form guideways, a pair of cylindrical dies having rectangular ends extending into said guideways, a number of axially extending inserts of wear resistant material positioned in the surface of said dies, and means for adjusting the position of said rectangular die ends in said guideways.

HARRY BLOUNT.
